UNITED STATES PATENT OFFICE.

RICHARD RICE, OF VIRDEN, ILLINOIS, ASSIGNOR OF ONE-HALF TO HARRY VIVIAN,
OF VIRDEN, ILLINOIS.

DESIGN FOR A FUSE CUTTER AND SPLITTER.

59,774.

Specification for Design.

Patented Nov. 22, 1921.

Application filed June 6, 1921. Serial No. 475,455. Term of patent 3½ years.

To all whom it may concern:

Be it known that I, RICHARD RICE, a citizen of the United States, residing at Virden, in the county of Macoupin and State of Illinois, have invented a new, original, and ornamental Design for Fuse Cutters and Splitters, of which the following is a specification, reference being had to the accompanying drawing, forming part thereof.

The drawing is a front view of a fuse cutter and splitter showing my new design.

I claim:

The ornamental design for a fuse cutter and splitter, or the like as shown.

RICHARD RICE.
